UNITED STATES PATENT OFFICE.

CHARLES S. WERNER, OF BUTTE, MONTANA.

RADIATOR FOR AUTOMOBILES.

1,372,581.

Specification of Letters Patent. Patented Mar. 22, 1921.

Application filed September 4, 1918. Serial No. 252,565.

To all whom it may concern:

Be it known that I, CHARLES S. WERNER, of Butte, in the county of Silverbow and State of Montana, have invented certain new and useful Improvements in Radiators for Automobiles; and I do hereby declare the following to be a full, clear, and exact description of the invention, such as will enable others skilled in the art to which it appertains to make and use the same.

This invention relates to an improvement in radiators for automobiles.

The invention consists of fluted expandable tubes connected to the headers of a radiator, and to one of the tubes is attached a heater for heating and causing the circulation of the water in the system to eliminate the possibility of freezing. The heater is located in front of the tubes and is concealed from view by a perforated shutter which is located in front of the radiator and supported by the casing of the radiator.

The invention consists of certain novel features of construction and combinations of parts which will be hereinafter described and pointed out in the claims.

In the accompanying drawings:

Figure 1 is a longitudinal sectional view; Fig. 2 is a similar view at right angles 30 to Fig. 1;

Fig. 3 is a view in front elevation; and Fig. 4 is a detail sectional view on line 4—4, Fig. 1.

In the drawings, 1 represents the upper header and 2 the lower header which are connected together by tubes 3. The tubes 3 are constructed of a plurality of vertical tubular portions with flat portions intermediate the tubular portions, and in a manner 40 to allow them to expand and contract, due to overheating or freezing.

Supported on the lower header 2 is an alcohol lamp 4, extending entirely across the front of the radiator. A lip 5 on the lamp 45 extends through a slot 6 formed in a flange 7 extending outwardly from the header 2, and a similar flange 8 is located beneath the lamp for supporting it in position.

A tubular housing 9 is slidably mounted 50 on one of tubes 3 and is located over the burner of the lamp 4. An opening 10 is formed in the housing 9 whereby the burner may be lighted, and a sliding door 11 is provided on the housing for closing the opening.

55 Within the housing 9 is a heating drum or pan-like member 12 which is attached in

juxtaposition to one of the tubes at the front of the radiator, and which tube I have designated 3^a, the point of attachment forming an inlet to the pan, outlet therefrom being through the top of the pan by way of a pipe or tube 13 which leads to the upper portion of the tube 3^a. It will be seen that the pan-like member presents an extended surface over which the circulating water is spread which insures maximum heating efficiency. The tube 3^a has a lower extension 14 which projects well into the header 2 so that the water near the bottom thereof may be drawn or taken into the drum and heated 70 and then discharged through the tube 13 to the tube 3^a and upper header 1. In this manner, the water is kept in circulation throughout the system when the engine is not running, and the water is taken from 75 the lower header at a point where there is the greatest liability of freezing.

A casing or jacket 15 is adapted to be removably fitted over the headers and tubes, and is secured to the sub-frame 16 of the 80 automobile by bolts 17, 17.

The casing 15 is provided along its forward edges with suitable guides 18 for the reception of flanges 19 of a protector or shutter 20 which is removably fitted to the 85 casing. The shutter or protector is provided with a plurality of openings or perforations 21, 21 for the admission of air to the tubes for the purpose of cooling.

A slide or damper 22 is mounted on the 90 inner side of the protector or shutter and is provided with openings 23 adapted to register with the openings of the protector or shutter. A knob 24 is connected to the damper 22 and extends through the protector or shutter so that the damper may be operated for closing the openings of the shutter or for regulating the amount of air to be admitted to the tubes for the purpose 95 of cooling. When the damper 22 is in 100 closed position the cold air is shut off from the tubes and the water can be heated by the heating means if desired, should the temperature be such that it is necessary to use it.

105 In extreme warm weather the shutter may be removed and thereby provide an unobstructed path for the air to circulate about the tubes for cooling them.

The shutter is preferably semi-circular in 110 cross-section, thereby affording ample space for the heater.

The filling tube 25 of the header 1 is provided with an exhaust pipe 26, which extends outwardly and upwardly into a steam trap 27 formed on the side of the tube 25. 5 The pipe 26 allows the steam generated in the header to exhaust into the trap. A partition 28 extends from the top of the trap downwardly for a short distance, thereby dividing the trap into two chambers or compartments, and causing the steam to pass 10 downwardly, after being discharged from the exhaust pipe 26, from one chamber and beneath the partition before entering the other chamber. The steam is conducted 15 from the last mentioned chamber by a pipe 29 which extends downwardly and below the radiator.

As the steam enters the trap and passes from one chamber to the other, any water 20 of condensation will collect in the bottom of the trap 27. An opening 30 formed in the outwardly extending portion of the pipe 26 allows the water to be returned to the radiator through the pipe 26.

25 I claim as my invention:

1. A radiator having, an upper and a lower header, a plurality of tubes connecting

said headers, a pan like member in juxtaposition to said tubes having an inlet connection with one of said tubes and an outlet 30 connection near the upper end of one of said tubes, and a heating element beneath said pan like member to heat the water, thereby causing its circulation.

2. An automobile having, in combination, 35 a radiator comprising an upper and lower header, a plurality of tubes connecting said headers, one of said tubes extending into the lower header, a pan like member having an inlet connection with said tube and an 40 outlet connection near the upper end of one of said tubes, a heating element beneath said pan like member, a housing for said heating element and pan, a detachable perforated shutter mounted in front of said radiator tubes, and a damper carried by said shutter for regulating the flow of air therethrough. 45

In testimony whereof I have signed this specification.

CHARLES S. WERNER.
